METALWORKING MACHINE

Carl C. Grotnes, Park Ridge, Ill.

Application April 25, 1938, Serial No. 204,042

15 Claims. (Cl. 153—2)

The invention relates to machines for shaping sheet metal articles such, for example, as cylindrical shells or blanks used in making pails, buckets and the like, and has for its principal object the provision of a unitary machine for not only edging the blank but also forming a bead therein all as part of a single operation.

A further object of the invention is to provide a combined roll edging and beading machine for operating on cylindrical metal blanks in which the respective edging and beading dies are operated in timed relation to shape the blank expeditiously and economically.

Another object of the invention is to provide in a cylindrical blank shaping machine an improved transfer mechanism for automatically presenting successive blanks to the shaping dies.

The invention also resides in various structural improvements in the mechanism for stripping the shaped blanks from the dies.

Further objects and advantages of the invention will become apparent from a consideration of the following description taken in conjunction with the accompanying drawings in which:

25 Figure 1 is a perspective view of a metal working machine embodying the invention.

Fig. 2 is a perspective view of one of the finished blanks after it has been operated on by the machine in Fig. 1.

30 Fig. 3 is an enlarged longitudinal sectional view along the line 3—3 in Fig. 1.

Fig. 4 is a vertical sectional view along the line 4—4 in Fig. 3.

35 Fig. 5 is a longitudinal sectional view along the line 5—5 in Fig. 3 illustrating particularly the transfer mechanism with a series of work blanks in position thereon.

40 Figs. 6 and 7 are enlarged fragmentary front elevations of the die head with the beading die in respectively contracted and expanded positions.

Fig. 8 is a detailed perspective view of one of the die blocks included in the beading die.

45 Fig. 9 is a detailed transverse sectional view along the line 9—9 in Fig. 3.

For purposes of illustration of its various novel features, the invention has been shown and described herein as embodied in a machine for forming a rolled edge 10 and annular bead 11 in cylindrical blanks 12 (Fig. 2) such as are used 50 in fabricating pails for paint and the like. It will be apparent to those skilled in the art, however, that the invention is applicable in many of its aspects to machines for shaping other articles. In general, the particular machine illus-

trated (Fig. 1) embodies a bed 13 on which is mounted an axially reciprocable die breast or head 14 carrying a circular roll edging die 15 and an expandable beading die 16 on its forward end. Plain cylindrical sheet metal blanks are presented to the dies in axial alignment with the head 14 by transfer mechanism 17 which moves the blanks step by step transversely of the machine. As the head 14 advances, the blank is forced against an adjustable abutment or stop 18 and a rolled edge is formed on the end of the blank facing the head 14 by the roll edging die 15. In the course of this same advancing movement of the head the beading die 16 is inserted within the blank and upon the completion of the roll 15 edging operation the beading die is expanded to engage the blank and form the annular bead 11 therein. The beading die 16 is then retracted out of engagement with the blank and the head 14 returned to its initial position. The transfer mechanism 17 serves to present successive blanks to the dies in timed relation with the die head movement so that the machine operates entirely automatically.

The edging die 15 (Figs. 4 and 6) has been shown in the form of a ring-shaped plate bolted to the forward end of the die head and provided with an annular groove 19 which receives the forward edge of the cylindrical sheet metal blank 12. As the head 14 advances to the position shown in Fig. 4 the blank is forced against the stop 18 so that the forward edge of the blank is curled outwardly and back by the groove 19 as shown in Fig. 4 to form a suitably rolled reinforcing or strengthening edge 10 on the blank. If the stop 18 is used simply as an abutment and guide it may have a plain flat surface. In the event, however, that it is desired to expand the outer edge of the blank in flange form to shape it for the connection of a bottom wall member as indicated at 10a, a truncated cone-shaped projection 20 is provided on the face of the stop 18 (Fig. 4). In such case the stop 18 and projection 20 serve as a second opposed edging die and the opposite ends of the blank are shaped simultaneously by the compression of the blank between the die 15 and stop 18. In order to accommodate blanks of different axial length, the abutment 18 is adjustably mounted on the bed 13 (Fig. 1) by a screw 21.

The beading die 16 (Fig. 6) is composed of a plurality of die blocks 22 arranged in the supporting structure of the head 14 in a circular series and supported and guided for radial movements. For this purpose each of the die blocks 55

22 (Fig. 8) is provided with radially extending grooves 23 in its opposite faces which receive complementary projections or guide ribs 24 (Fig. 7) on a circular retaining plate 25 and on the 5 face of the ring-shaped edging die 15. The retaining plate 25 is mounted in spaced relation to the front of the edging die 15 by series of through bolts 26 surrounded by spacing collars 27. Retention of the segmental beading die blocks 22 in 10 their normally retracted positions is effected by a circular helical spring 28 positioned in annular grooves 29 in the outer ends of the blocks. When in its retracted condition the beading die is of 15 sufficiently small diameter that it may be moved freely into the interior of the blank.

For the purpose of forcing the beading die blocks 22 radially outward into engagement with the blanks, a cone-type actuator is employed. For this purpose a cone 30 (Fig. 3) is secured 20 to the outer end of an axially reciprocable draw bar 31 slidably supported in a central bearing sleeve 32 bolted within an axial bore 33 in the head 14. To accommodate the actuator the die 15 has a central opening 15^a aligned with a 25 counterbore 33^a in the face of the head 14. The conical surface of the actuator 30 has flattened bearing surfaces for engagement with the inner ends of the respective die blocks 22 so that when the actuator is thrust outwardly from the position 30 shown in Fig. 4 to the position shown in Fig. 3, the die blocks 22 are correspondingly moved outwardly from their retracted positions (Fig. 6) to their radially or laterally projected positions (Fig. 7).

35 The head 14 constitutes a reciprocatory slide upon which the two dies 15 and 16 are mounted for movement axially of the work. To form the rolled edge and the bead, the two dies are operated in a predetermined timed relation, the arrangement being such that as an incident to the movement of the die 15 with the head to form the rolled edge, the die 16 is positioned for subsequent radial expansion by an independent movement of the actuator 30 relative to the head to form the 40 bead. In the present instance the head is of generally cylindrical contour and is supported for axial movement on the bed 13 of the machine through the medium of axially extending side ribs 34 (Figs. 3 and 9) disposed in guideways 45 formed by the bed and by retaining plates 35. These retaining plates are bolted to the sides of the bed and are provided with flanges 36 overlying the ribs 34 on the head.

Timed sequential actuation of the dies and 50 their supporting head is effected by a driving mechanism which serves in general first to advance the head 14 to the position shown in Fig. 4, in which the edging die 15 engages the blank 12 and forms a rolled edge thereon, second, to expand the beading die into engagement with the blank as shown in Fig. 3, third, retract the beading die to its initial position, and finally, retract both of the dies out of engagement with the blank and return the head 14 to its initial position. This 55 power actuated mechanism includes a pair of gears 37 (Fig. 3) journaled in the bed 13 on shafts 38 and connected by an eccentric crank pin 39, the gears being driven by an electric motor (not shown). Fixed on the outer faces of the gears 60 37 are peripheral cams 40 engaged by cam follower rollers 41 journaled on head 14. The thrust exerted by these cams on the followers 41 advances the head 14 from its initial position to its 65 fully projected position (Fig. 4). The cams are 70 contoured so that a period of dwell follows in

which the head 14 remains stationary. During this dwell, the movement of a pitman 42 connected between the eccentric crank pin 39 and the draw bar 31 projects the cone shaped actuator outwardly with respect to the head so that the 5 beading die is thrust into engagement with the blank. Further movement of the pitman 42 during the dwell period retracts the draw bar 31 to its initial position so that the actuator 30 is again in the position shown in Fig. 4 at the completion of the dwell. The spring 28 thereupon contracts the beading die to its initial diameter. 10

In addition to their function in actuating the beading die 16, the cone-shaped actuator 30 and the associated driving connections also serve to 15 positively retract the head 14. Thus, upon continued rotation of the gears 37 to their initial position, the head 14 is pulled to its starting position by the pitman 42 and draw bar 31 due to the engagement of the rear face of the actuator 30 20 with a shoulder 43 (Fig. 4) at the bottom of the counterbore 33^a. It will be understood that if desired more than one set of beading dies may be placed in the head 14 and actuated in timed 25 relation to each other and to the edging die. 25

Successive blanks are automatically presented to the machine in timed relation to the movement of the dies and then ejected from the machine after being shaped so that the constant attention of a workman is not required. The transfer mechanism 47 (Figs. 3 and 5) for this purpose embodies reciprocating means for positively pushing the blanks 12 step by step along a path transverse to the line of reciprocation of the die carrying head 14, and for locating successive 30 blanks in operative alignment with the dies. In the construction illustrated a plurality of blanks 12 are advanced simultaneously by a series of 35 pushers 48-49-50 carried on a horizontally reciprocable rack 51. These pushers are tiltably 40 mounted on the rack so that they can be depressed and slid under the blanks on the return stroke of the rack (to the left as viewed in Fig. 5) and then raised into pushing engagement 45 with the blanks (as shown in Fig. 5) on the opposite or advancing stroke of the rack. A common drive mechanism, hereinafter described in greater detail, is utilized for reciprocating the rack 51 and for tilting the pushers 48-49-50 so that the reciprocating and tilting motions of 50 the pushers will occur in timed relation. As shown, the rack is formed of spaced channels 52 (Fig. 1) joined by webs 53 and journaled on rollers 54 secured to the machine bed 13 by 55 brackets 54^a. 55

Fresh blanks 12 are rolled onto the transfer mechanism by a pair of spaced stationary inclined runways 55 (Fig. 5) having notches 56 in their upper surfaces for receiving the blanks at sequential points in their step by step progress. The pushers 48-49-50 advance the blanks from one notch to the next upon each reciprocation of the rack 51. To support a blank in operative alignment with the head 14 the last pusher 50 in the series is notched out at 50° to cradle and receive a blank forced against it by the next adjacent pusher 49. These two pushers 49 and 50 thus cooperate to hold the blank against lateral displacement while it is being operated upon by the dies. 60

Movement of the blanks 12 transversely with respect to the die head 14 is guided not only by the abutment 18 but also by an opposed guiding mechanism including vertical guide plates 57 (Fig. 1) secured to a rigid rectangular frame- 70 75

work 58 surrounding the forward end of the head 14. These guide plates present smooth flat surfaces spaced a distance from the abutment 18 substantially equal to the length of the blanks being operated upon. To guide the blanks 12 into the space between the plates 57 and abutment 18 the leading edge 57^a of the first of the plates 57 is bent out so that the blanks will slide transversely of the rack 51 into proper position if they are located too close to the head 14 as they move onto the machine. This guiding mechanism also includes a horizontal guide bar 59 pivoted on the frame 58 at 60 and adapted to ride over the tops of the blanks as they move into position in front of the head 14. The weight of the pivoted bar 59 forces the blanks down against their supporting pusher 50 so that they will be accurately alined with the dies.

In order to coordinate the actuation of the transfer mechanism 17 with that of the die head 14, they are preferably driven from the same prime mover. In the machine shown a lever 61 (Figs. 1 and 3) pivoted in a bracket 62 on the side of the machine bed is intermittently oscillated by a cylindrical grooved cam 63 fast on the gear shift 38. This intermittently oscillating lever 61 not only tilts the pushers 48-49-50 but also reciprocates their supporting rack 51 through the medium of a lost motion connection. To this end the pushers 48-49-50 are mounted on bell crank levers 64 pivoted on the rack 51 by pivot pins 64^a and pivotally connected at their lower ends to a rod 65 (Fig. 5) slidable in the rack, the outer end of this rod being connected to the oscillating drive lever 61 through a link 66. The lost motion connection of the rod 65 to the rack is formed by spaced collars 67-68 fast on the rod 65 and engageable with the opposite faces of the transverse rack web 53. The first part of the inward stroke of the rod 65 to the left (as viewed in Fig. 5) tilts the pushers 48-49-50 downwardly and then the engagement of the collar 67 with the rack web 53 shifts the entire rack and pusher assembly inward during the remainder of the stroke. Since the pushers are thus depressed below the level of the blanks 12 they pass freely under them during this inward stroke of rack and pusher assembly. Similarly, the first part of the outward stroke of the rod 65 (to the right as viewed in Fig. 5) tilts the pushers 48-49-50 upward again and then the engagement of the other collar 68 with the rack web 53 shifts the rack and pusher assembly outwardly to its initial position. During this outward stroke the raised pushers engage the blanks and move each of the series one step forward. In this manner the blanks are positively advanced step by step to operative engagement with the dies 14-16, and upon completion of the die forming operation the finished blanks are pushed from the machine by the last pusher 50.

In order to prevent premature movement of the rack 51 a friction plate 69 (Fig. 1) is preferably secured to one of the channels 52 to engage the rollers 54 when the rack 51 is in its extreme inward position (to the left as viewed in Fig. 1) so that only a positive pull by the collar 68 on the rack web 53 will dislodge the jammed plate 69 and permit the rack 51 to move outwardly.

Stripping of the finished blanks 12 from the dies 15-16 is accomplished by the horizontal guide bar 59. This guide bar rides on the top of the blank between the rolled edge 10 and bead 11 so that when the die head 14 is retracted the sta-

tionary bar 59 will engage the bead 11 and thereby strip the blank from the dies in the event that the blank tends to adhere to the die 15. Accordingly the finished blank is readily ejected from the machine by the next pushing stroke of the 5 pusher 50.

The guide mechanism may also be utilized to strip the shaped blank from the flange forming projection 20 on the abutment 18 in the event that such a forming abutment is used. For this purpose the guide supporting frame 58 is carried by a pair of bars 70 journaled for horizontal sliding movement in lugs 71 projecting from the bed side plates 35 (Fig. 1). Adjustable collars 72 and 73 on the rods 70 are engageable by lug 74 on the 10 side of the head 14 which projects through a slot 75 in one of the side plates 35. With the collars 12 and 73 positioned as shown in Fig. 1, the guide frame 58 will, of course, remain stationary while the head is reciprocated. When it is desired to 15 use the guide mechanism to strip the blanks from the stop 18, the collar 73 is moved along the rod 70 away from the adjacent projection 71 and made fast to the rod in this adjusted position. Then the return or retractive stroke of the head 20 25 25 will cause the lug 74 to engage the collar 73 so that the entire guide frame 58 will be retracted during the final portion of the head return stroke. This retractive movement of the guide frame 30 causes the horizontal guide bar 59 to engage the 35 rolled edge 10 formed on the forward end of the finished blank and thereby pull the blank free of the projection 20 on the abutment 18. Similarly, on the next advancing stroke of the head 35 35 40 the lug 74 engages the other collar 72 so as to return the guide frame to its normal working position for engagement with the next blank presented to the machine.

Although a particular embodiment of the invention has been shown and described in some detail for purposes of illustration, there is no intention to thereby limit the invention to such preferred embodiment but, on the other hand, the appended claims are intended to cover all modifications within the spirit and scope of the invention.

I claim as my invention:

1. In a machine of the character described, means for supporting a cylindrical metal shell, a die head reciprocable toward and away from said support axially of a shell thereon, a roll edging die and a beading die carried by said head, a first power actuated means for advancing said head toward said support to engage the blank by said edging die with a period of dwell at the end of 55 said advance movement, and a second power actuated means operable in timed relation with the first for moving said beading die into and out of engagement with the blank during said period of dwell and for thereafter returning said head 60 to its initial position.

2. In a machine of the character described, means for supporting a cylindrical metal shell, a die head reciprocable toward and away from said support axially of a shell thereon, a ring shaped 65 roll edging die carried on the front face of said head, a radially expandable beading die disposed on said head forwardly and centrally of said edging die, a first power actuated means for advancing said head toward said support to engage the 70 blank by said edging die with a period of dwell at the end of said advance movement, and a second power actuated means operable in timed relation with the first for expanding the inserted beading die into engagement with the blank and 75

contracting the same again during said period of dwell and for thereafter returning said head to its initial position.

3. In a machine of the character described, 5 means for supporting a cylindrical metal shell, a die head, means for effecting relative traversing movement between said head and support axially of a shell thereon, an edging die on said head engageable with the adjacent edge of the shell, 10 said support including an abutment at the end of the shell opposite said head and cooperable with the latter to clamp the shell therebetween, a beading die also carried by said head and positioned forwardly of said edging die within the shell when, 15 said edging die is positioned in engagement with the shell, and means for actuating said beading die laterally into engagement with the shell in timed relation with the relative movement between said head and support and after the shell 20 is clamped by said head and support.

4. In a machine of the character described means for supporting a cylindrical metal blank, a die head traversable toward and away from said support axially of the blank and having a 25 bore therein alined with the axis of the blank, said supporting means including an abutment bearing against the end of the blank opposite said head, a ring shaped edging die on the forward end of said head encircling the end of said bore, 30 and engageable with the blank to clamp the same against said abutment, an expansible beading die on the forward end of said head and insertable into the blank, an actuator for said expansible beading die projecting through said bore, and 35 power actuated means for moving said head and actuator in timed relation.

5. In a machine of the character described, means for supporting a cylindrical metal blank, a die head traversable toward and away from said 40 support axially of the blank and having a bore therein alined with the axis of the blank, a ring shaped edging die on the forward end of said head encircling the end of said bore, an expansible beading die in the forward end of said head 45 and insertable into the blank, actuating means for said beading die including an axially slidble draw bar in said bore, means including a rotatable cam for advancing said head toward said support with a period of dwell at the end of the advance, 50 means for projecting said draw bar forwardly of said head to expand said beading die and for returning said draw bar through a full return stroke equal to the advance of said head, means on said head engageable by said bar to effect a withdrawal 55 of said head by the return stroke of said draw bar, and common power actuated means for driving both said head advancing means and draw bar.

6. In a machine of the character described, 60 means for supporting a cylindrical metal shell and including an abutment engageable with one end of the shell; an edging die; a beading die; and power actuated means for simultaneously advancing said dies to a position in which said 65 edging die engages the shell and the other does not, retaining said edging die in such position for a period of dwell while moving said beading die into and out of operative engagement with the shell and then simultaneously returning both dies 70 to their initial positions, said edging die being effective in said first named position to clamp the shell against said abutment.

7. In a machine for roll-edging and beading a cylindrical shell, the combination of a roll-edging 75 die, a bead forming die adapted to be inserted

into the shell, a clamping abutment arranged in opposed spaced relation to said roll-edging die, means for effecting relative movement between said edging die and shell axially of the shell to bring said edging die into operative engagement therewith to not only edge the shell but also to clamp the same in position against said clamping abutment and for simultaneously effecting relative movement between said beading die and shell to position said beading die adjacent the shell, means operative in timed relation with said first named means to move the inserted beading die into engagement with the shell upon completion of the edging operation, and means for simultaneously effecting a disengaging movement between both of said dies and the shell.

8. In a machine for roll-edging and beading a cylindrical shell, the combination of a roll-edging die, an expansible bead forming die adapted to be inserted into the shell, a clamping abutment arranged in opposed spaced relation to said roll-edging die means for effecting relative movement between said edging die and shell axially of the shell to bring said edging die into operative engagement therewith to not only edge the shell but also to clamp the same in position against said clamping abutment and for simultaneously effecting relative movement between said beading die and shell to insert said beading die within the shell, and means operative in timed relation with said first named means to expand the inserted beading die into engagement with the shell upon completion of the edging operation.

9. In a machine for shaping cylindrical sheet metal blanks, a pair of spaced and opposed circular edge shaping dies, first power actuated means for effecting relative movement between said dies to engage the respective ends of a cylindrical shell positioned therebetween, a beading die insertable into the shell while said first named dies are in engagement with the shell and thereby holding it against movement, and a second power actuated means operable in timed relation to the first for moving said beading die into and out of engagement with the shell.

10. In a machine of the character described the combination of means for supporting a cylindrical metal shell, a head mounted for reciprocation toward and away from said support axially of a shell thereon, a beading die on the forward end of said head insertable into the shell to form a bead therein intermediate its ends, and means including a horizontal guide member resting on the shell when positioned on said support means for engaging the bead formed therein to strip the shell from said beading die upon the withdrawal of said head and for guiding successive shells into position on said support.

11. In a machine of the character described, a transfer mechanism for presenting successive cylindrical metal blanks to a die mechanism or the like comprising an inclined runway for supporting a series of cylindrical blanks for rolling movement toward said beading means with the blanks disposed in parallel relation, said runway having notches therein for receiving and holding the blanks in successive positions in a step-by-step advance thereof, a reciprocatable rack extending along said runway beneath the surface thereof, a plurality of pushers tiltably mounted on said rack, actuator means for tilting said pushers alternately above and below the surface of said runway to bring the same alternately into and out of pushing position with respect to the blanks.

- and means for reciprocating said rack in timed relation with the tilting of said pushers.
12. In a machine of the character described, a transfer mechanism for presenting successive cylindrical metal blanks to a die mechanism or the like comprising, means for supporting a series of cylindrical blanks disposed in parallel relation, a reciprocatable rack extending beneath said last named means transversely to said blanks, a plurality of pushers tiltably mounted on said rack, actuator means for tilting said pushers alternately upward into engagement with the blanks and downward out of engagement therewith to bring the pushers alternately into and out of pushing position with respect to the blanks, and means including a lost motion connection for connecting said actuator in driving relation with said rack to reciprocate the same in timed relation with the tilting of said pushers.
13. In a machine of the character described, a transfer mechanism for presenting successive cylindrical metal blanks to a die mechanism or the like comprising, means for supporting a series of cylindrical blanks disposed in parallel relation, a reciprocatable rack extending beneath said last named means transversely to the blanks, and a plurality of pushers movably mounted on said rack and adapted to project upwardly from said rack and operatively engage the blanks during the forward movement of the rack and to be tilted downwardly out of the path of said blanks during the backward movement of said rack, at least one of said pushers having a recess formed
- in the rear side thereof adapted to cradle a blank pressed against the same by the next adjacent pusher, to thereby position such blank with respect to the die mechanism or the like.
14. In a machine of the character described, means for supporting a cylindrical metal shell, a die support, a roll edging die and a beading die carried by said die support, a first power actuated means for effecting a relative advancing movement between said supports axially of a blank carried by the support to engage the blank by said edging die with a period of dwell at the end of said advance movement, and a second power actuated means operable in timed relation with the first for moving said beading die into and out of engagement with the blank during said period of dwell and for thereafter effecting relative movement between said supports to return the same to their initial positions.
15. In a machine of the character described, the combination of a fixed die for shaping the edge of a cylindrical metal shell, a reciprocable head for pushing a shell into engagement with the die, a stripper presenting an elongated edge extending transversely across the periphery of the shell intermediate the latter's ends when the shell is in engagement with the die, and power actuated means for withdrawing said head from shell-engaging position and sequentially moving said stripper endwise of the shell away from said die into engagement with a curl on the opposite end of the shell to strip it from the die.

CARL C. GROTNES.
